CLAIM

The ornamental design for a cork deck stand up paddle board, as shown.

DESCRIPTION

FIG. 1 is a top perspective view of a cork deck stand up paddle board, showing my new design;

FIG. 2 is a front elevation view thereof;

FIG. 3 is a rear elevation view thereof;

FIG. 4 is a right-side elevation view thereof;

FIG. 5 is a top plan view thereof;

FIG. 6 is a bottom plan view thereof; and,

FIG. 7 is a cross-sectional view thereof, taken generally along lines 7-7 of FIG. 5.

The stipple texture on the claimed design represents cork and forms part of the claimed design.
